Application October 6, 1948, Serial No. 53,103

7 Claims. (Cl. 123—32)

1

This invention relates to internal combustion engines, commonly referred to as the self-ignition type.

In engines of this character, it has been generally assumed to be necessary, and common practice has been to provide compression of the air prior to fuel injection in ratios of fifteen to eighteen or more to one. In fact, the modern trend is toward still higher compression ratios in attempts to improve combustion of the fuel oils commonly used.

An object of the present invention, therefore, is to provide a piston and cylinder combustion chamber of great simplicity, unique conformation and capable of creating the desired high temperature for ignition and combustion of such fuel oils, and which may operate most efficiently on compression ratios of, say, between nine and eleven to one.

A more specific object is to provide for a special relationship of direction of injection jets and space between the piston and cylinder head at the moment of ignition, which will avoid the impingement of unburned fuel against the surfaces, and which will cause the projection of the fuel into a specially created hot-zone of intensive air movement.

In carrying out my invention I so arranged the surface formation of the piston head and cylinder that on the stroke compressing the air a particular phenomenon of air movement is set up whereby it forms an annular zone (or ring) concentric with the axis of the piston, and in which zone the air is caused to revolve in directions such that each part of the air is caused to whirl in inwinding radial planes and in constantly narrowing inwinding whirl around a ring-like axis. This ring-like axis of whirl is concentric with the cylinder wall and the longitudinal axis of the piston. An object is to so shape the piston surface with relation to the inner surface of the cylinder head that this spinning action is commenced early in the compression stroke, and is continued with increased intensity and rapidity until the moment of greatest velocity of spin around this annular axis is in effect at the inner end of the piston stroke. At the end of the compression stroke this spinning ring of air is midway between the adjacent piston surface and cylinder head surface, and likewise is spaced outwardly from the center of the piston.

As the description proceeds, it will become more apparent that I create an annular spinning zone of air around a circular axis, and concentrate and intensify the spinning action to effectively cause

2

friction of the air to increase the temperature above that normally resulting from the compression. For convenience I refer to this spinning zone of air as a "friction ring." In other words, I create a high temperature friction ring of air and concentrate and intensify its spinning whirl, attaining temperatures at the center or annular axis of it substantially above the "adiabatic constant" surrounding air. At the instant of highest temperature within the "friction ring" fuel injection occurs—into the center of hottest zone—causing igniting before loss of temperature.

Still another object is to so shape a combustion surface at the center of the piston head that it effects an outward radial flow of air along the direction of the injection of the fuel jets at the moment of greatest compression.

More specific objects are to so shape the outer rim of the piston head surface and an intermediate zone and the raised center cone-shaped top or truncated surface thereof that these surfaces contribute to the increase and maintenance of this spinning core or friction ring of air, and that the highest possible speed of spin may be attained and maintained until ignition, and continued to some extent to assure complete combustion.

I am aware of various cone-shaped piston heads used in self-ignition engines of this nature and of various other shapes which include forming cavities in the piston or use of cavities in the cylinder head, and of special cavities in the cylinder head for pre-ignition, sometimes referred to as energy cells. The objects of such shapes are usually to effect turbulence and to provide a room or space for the ignition and beginning of combustion. In these spaces which form cavities or depressions, turbulence of some degree is effected usually for the general purpose of accomplishing the stirring action to assure intermingling of air with the fuel mixture at the beginning of combustion, and to some extent until combustion is complete. It may be noted that in most of these there is an effect, desired by some, to delay ignition. In the so-called inner cells of cavities outside the cylinder chamber in which ignition or pre-ignition is effected, likewise there is a turbulence caused to improve mixture and burning.

An essential difference in my invention over such devices and special surface formations, is that I am able to secure an ignition temperature of the spinning circular core of the air, i.e., the "friction ring," such as to correspond to higher compression ratios. Wherefore, it may be said that an essential object of my invention is to at-

tain efficient, uniform and complete combustion and instantaneous ignition in engines of this type while using a low overall compression ratio, such, for example, as about ten to one.

All conventional parts of such engines may be used with well-known fuel injection devices and equipment for a given horsepower. The cylinder, piston, connecting rods, crank, bearings, crank case, frame, etc., may all be of lighter weight and design, because of the greatly reduced impact and strain as compared with higher compression motors or engines of like nature.

Another advantage obtained by my invention is that my engine starts at the usual starting speeds and without the use of ignition devices, spark plugs, and the like. Somewhat higher, but still relatively low compression, self-ignition engines have special starting arrangements. For example, one well known engine running at just under twelve to one compression ratio utilizes a separate cavity which may be shut off, reducing the volume in the combustion chamber and increasing compression for starting purposes. Such a shut-off device, however, obviously adds expense and encounters trouble in maintenance, being subjected to the most severe temperatures and other damaging conditions. With my engine designed for approximately ten and one-half to one compression ratio, I have been able to start it readily after it had been idle in zero temperatures for a period of several days. The starting speed of turn-over of the crank shaft, in the instance given, was slightly above or about one hundred revolutions per minute.

In carrying out my invention I used a cylinder head which is sloped a few degrees. For example, seven degrees in a cone shape, and the rim of the piston and the height of the cylinder cone spreading surface at the center are so shaped as to attain the accomplished objects given above.

While my invention may be adapted to either two-cycle or four-cycle engines, in the embodiment shown, I have illustrated valves in the cylinder head, and the axis of these valves and their position in the head is such as to conform to the slope of the inner surface of the cylinder head.

As is well known, some two-cycle engines use a valve or valves in the head for certain functional and design purposes, and I do not wish the present invention to be limited to either form, but for the purpose of the present application the invention will be described as embodied in a design such as shown in the accompanying drawings, and which has proven successful in a four-cycle type self-ignition engine.

In the drawings, Fig. 1 is a vertical section through the upper portion of a cylinder with the piston at the upper end of the stroke;

Fig. 2 is a similar section showing the position of the piston part-way up on its compression stroke;

Fig. 3 is a similar section through the complete piston, on a somewhat enlarged scale;

Fig. 4 is a plan view of the top of the piston on the scale shown in Fig. 3;

Fig. 5 is a diagrammatic view showing the air movement near the upper end of the compression stroke of the piston;

Fig. 6 is a similar diagram illustrating the condition of the air at the top or inner end of the compression stroke, and at the time of firing;

Fig. 7 is a diagrammatic view illustrating the

fuel jets projected radially into the inner spinning zone of the air of the "friction ring."

Describing the parts by the use of reference characters, 1 designates the inner cylinder wall, and 2 the water jacket of the cylinder onto which is fitted a cylinder head member 3 having a water jacket 4 and two valves designated 5. The top of the cylinder chamber forms a conical wall surface 6. 10 indicates the fuel injection nozzle holder having a nozzle 11 provided with jets from which the fuel is forcibly sprayed in a plurality of fan-like streams indicated at F. Figs. 6 and 7.

The piston, as shown, comprises essentially a skirt 15, wrist pin bosses 16 and an upper or inner end wall 20, of novel formation. The central portion of this top or inner wall of the piston comprises essentially a conical formation 20 merging with a horizontal or radial flat portion 21, while at the outer portion or periphery the wall slopes upwardly forming a rim 22. A cross bracing rib or ribs, such as at 23, may be used to strengthen the head of the piston.

As stated for purposes of illustration, I have chosen a construction suited essentially to a four-cycle compression ignition engine. It will be understood that suitable mechanism may operate the inlet and exhaust valves 5 to admit air on a charging stroke and to effect the exhaust on the alternate stroke.

In attaining an effective increase of temperature, and the various other advantages outlined in the foregoing description, the particular shape and positioning of the various surface formations at the top of the piston coact with a slope of the cone-shaped inner surface of the cylinder head, and these surfaces and their relationships are critical.

The creation of turbulence during compression in engines heretofore known effects no appreciable increase in the temperature above the expected temperature which may be mathematically arrived at as a result of the ratio of compression.

As above indicated, I have discovered that with certain shapes and relationships of surfaces at the head of the piston and the cylinder head, a phenomenon of very highly spinning air may be created, which, apparently, by reason of its inwinding motion at extremely high speed, creates a zone of great friction, and probably, for a brief instant, a localized zone of compression greater than that resulting from the compression ratio alone.

I am aware that cone shapes have been formed on the top of the piston. I am familiar with the so-called "energy cells" in which the fuel is mixed with the air by agitation and turbulence. I am familiar with step formations and various other attempts to increase efficiency of the fuel burning. However, I believe that the phenomenon effecting quick and complete ignition as well as attaining remarkably uniform mixture for complete burning in a low compression engine is the result of my novel formations and relationships at the piston and cylinder head.

As illustrated in the drawings, the cone-shaped portion 20 is preferably approximately one-half of the diameter of the piston, at its base, and rises to a height of one-quarter of its diameter above a flat portion 21, which, in turn, is below the raised rim 22.

The top of the cone portion 20 is preferably flat, as indicated at 20b. The sloping top surface of the cone is provided with concentric curved-

bottom baffles 20c, three of these being shown as illustrative of the number and size desired. The rim 22 rises above the surface 21a to approximately one-half of the height of the cone. A conical surface 22a is sloped outwardly, approximately at thirty degrees, and the top of the rim has a narrow flat surface 22b of appreciable width, which, however, is not particularly critical.

These dimensions may vary somewhat while maintaining the approximate proportions. For example, the diameter of the base of the cone 20 may be from one-third to upwards of two-thirds of the piston diameter. The flat top 20b of the cone may have a diameter of about one-fourth to one-fifth of the base diameter.

The inner surface of the cylinder head and likewise the inner faces of the valves 5 should slope at an angle between five and ten degrees to attain the satisfactory relation to the contours 20 of the top of the piston. The slope of the surface 6 shown is seven and one-half degrees, in which case the fuel should be injected at an angle of about eighteen degrees from a plane normal to the axis.

At the top of the piston stroke the rim 22 should stop short of the adjacent surface of the cylinder head by about one-twelfth to one-fifteenth of the piston diameter. At the scale shown, the space between the top of the rim 22 and the adjacent cylinder head surface, at the top of the piston stroke, is about one-fourteenth of the piston diameter.

In Fig. 1 the valves 5 are shown closed. The piston having reached the top or inner end of the compression stroke has created the expected degree of compression and has also created the inward swirling air friction ring, into which the fuel is being injected.

In Fig. 2 the arrows A indicate the direction of air flow at a time during the inward stroke of the piston, the inlet valve having been closed after admitting the air, and the piston having started on its upward movement. There is still a downward surge of air from the vicinity of the inlet valve 6. Having filled the cylinder above the piston with fresh inrushing air, the upper portion of the air continues downwardly by momentum. At the same time the lower portion is started to turn back upon itself, beginning the annular swirl, being deflected radially and turned upon itself by the top surfaces of the piston, i. e., the cone 20, flat portion 21 and raised perimeter thereof.

The curving depressions forming concentric baffles 20c have been found to facilitate or add to the swirling effect, I believe, starting a series of outward and upward turns of the air on the inward stroke, with the final result of increasing the intensity of the swirling friction ring.

The diagrammatic view of Fig. 5 indicates the piston approaching the top or inner end of its stroke where the air, now further compressed, is being turned inwardly upon itself, as shown by the arrows.

Fig. 6 indicates the final effect of the concentrated swirling friction ring, the greatest speed of whirl being at the center, as indicated by the arrows at 30. Around this annular central core inwinding air as at 31 is whirling inwardly upon it. Outer streams or spiral layers of the whirling ring may be visualized as by the arrows 32.

In Fig. 4 the position of the core of this air friction ring with relation to the piston is shown diagrammatically by the spiral and arrows 30.

Here, the progressive layers, which, in fact, may constitute a very large number of inwinding layers in the form of rings of air, are again indicated by the spirals 31 and 32.

To visualize the friction ring, one may liken its formation to that of a smoke ring which holds its shape by whirling upon itself. There, however, the analogy ceases. The air friction ring produced, as described, is under compression, and the speed and momentum of the whirl causes an intense concentration at the core of this air friction ring. This zone or ring of intense concentration is believed to correspond to the whirl indicated by the arrows 30. It is into this concentrated zone or core 30, of momentarily increased pressure and great friction, that the fuel streams F are injected, at the usual very high pressures of two thousand pounds or more per square inch.

From studies of the results attained, there is every reason to believe that the temperatures in the whirling ring-like zone 30 are substantially higher than would result from the ratio of compression used. Furthermore, this swirl by which the intense friction and higher temperature is effected continues as the down or outward stroke of the piston begins, effecting a mixing of the air and burning fuel and resulting in more complete combustion and even burning, and through a longer than usual effective part of the power stroke.

The direction of the fuel jets is at an angle midway between the general angle of the baffle surfaces 20c of the slope of the cone from the surface 20b down to the surface 21a, and the slope of the cylinder head surface. This is obviously desirable in that it avoids impingement of liquid fuel upon the piston and cylinder surfaces. The intensity, force and compactness of the swirling friction ring arrests the projected fuel streams. Thus, while fuel jet liquid may penetrate the core of the friction ring, it does not reach the cylinder wall or the raised perimeter 22 of the piston toward which the jets are directed.

Inspection of the surfaces after running indicates there has been no liquid fuel striking against the cylinder or piston surfaces. Likewise, analysis of the exhaust proves that I have attained complete combustion, with various grades of fuels, than is possible even with much higher compression self-ignition engines heretofore known.

The resulting power is delivered most effectively, beginning with the start of ignition at the innermost part of the stroke the combustion continues over a longer portion of the stroke than usual. An important result is that the entire engine may be designed with smaller bearings and lighter parts in proportion to the power delivered. It follows that this is necessarily a great advantage resulting from the comparative complete freedom from "knock." Other advantages are gained by avoiding ignition prior to the end of the compression stroke, while effecting a complete and relatively gradual or extended combustion on the power stroke.

In a motor having a piston and cylinder design, such as shown in the drawings, an example of suitable dimensions may be a piston and cylinder diameter of four and seven-eighths inches and six inch stroke with a displacement volume of one hundred and twelve cubic inches and a clearance volume at the inner end of the piston stroke of eleven and eight-tenths cubic inches. At this point the surface of the cone of the piston, that

is, the truncated surface, is about three-eighths of an inch from the cylinder surface. The fuel injection pressure may be lower than usual, but for ordinary purposes I use the conventional injection pumps capable of forcing the liquid fuel into the combustion chamber at two thousand to two thousand five hundred pounds, which being substantially lower than is customary, results in less wear on the injection system, and, incidentally, effects saving of power to operate it.

The complete burning low compression factors contribute to more economical cooling in the water jacketed zone. In other words, we have attained a higher thermal efficiency and require less cooling for a given horsepower.

I claim:

1. A cylinder with a nearly flat conical head surface, and a piston with a cone and a surrounding flat surface and raised rim forming a chamber at the inner end of the compression stroke in which the walls are separated, and means for injecting radial streams of fuel at an angle midway between the cone surface on the piston and the slope of the conical surface of the cylinder head, whereby the fuel is ignited in a whirling ring of air, the cone having a flattened top surface of about one-seventh of the diameter of the piston, and the slope of the cone and the cylinder wall being divergent at an angle substantially twenty to twenty-five degrees.

2. A self-ignition engine adapted to start and run on compression ratios lower than 12 to 1, and having a piston and cylinder which form the complete combustion chamber and ignition means, the piston having its inner end provided with a central cone with a flattened area of approximately one-sixth of the diameter of the piston, and having a side wall formed generally on a thirty degree slope terminating at a substantially flat smooth radial surface extending from an inner edge of a diameter of about one-half the diameter of the piston, and having its outer edge about three-fourths the diameter of the piston, and meeting an upwardly sloping smooth surface extending at approximately thirty degrees to a narrow edge or rim at the perimeter of the inner face of the piston, the cylinder head surface comprising a flat cone of seven to ten degrees, a fuel injection nozzle projecting therethrough at the center, the head surfaces and cylinder head defining the complete combustion chamber.

3. The engine defined in claim 2 in which inlet and exhaust valves are provided in the cylinder head and are each mounted to present their inner faces on a slope conforming to the slope of the cylinder head.

4. The engine described in claim 2 in which the nozzle directs a plurality of radial spray streams midway between the slope of said cone and the slope of the cylinder head, and in which the piston and cylinder surfaces cause the air being compressed to form an extremely high speed inwinding friction air ring, the circular axis of which is about two-thirds or three-fourths the diameter of the piston.

5. The engine described in claim 2 in which the cone surface is provided with a series of annular concentric grooves each comprising approximately a one-fourth toroidal surface.

6. The structure described in claim 2 in which the cone surface of the piston is formed of three concentric stepped curves, the outer and lower edge of which is in a substantially radial plane, and each of the curved steps having a cross-sectional extent of approximately one-fourth circle and each of which projects a separate layer or stream of air toward an inwinding toroidal high pressure and high friction air ring.

7. A self-ignition engine adapted to start and run on compression ratios of between 10 and 12 to 1, and without starting or firing aids, and having a piston and cylinder, a cylinder head having an inside surface extending in a uniform direction to the full diameter of the cylinder and on a slope less than ten degrees, inlet and exhaust valves in the cylinder head, a centrally positioned fuel injection nozzle for directing a plurality of radial streams of fuel at an angle slightly spaced from an inner head surface, the surfaces of the piston head being shaped to form a central cone having a base portion of slightly more than one-half of the diameter of the piston and having side wall surfaces generally sloping at about thirty to forty degrees, the cone having a small portion at its apex omitted to shorten the cone in alignment with the injection nozzle and whereby the surface of the piston and cone are permitted to move into closer proximity, the side walls of said cone portion having formed thereon three or more concentric annular and outwardly curved trough-like baffle surfaces arranged in progressive steps from the top to the bottom of the cone, the piston having a substantially flat radial surface projecting outwardly from the cone and having an upwardly sloping uniform surface extending from the flat surface and rising about one-half the height of the cone and terminating near the periphery of the top of the piston, and the inner surface of the cylinder head and cylinder wall and piston head surfaces forming the complete combustion chamber, and whereby as the piston moves inwardly on the compression stroke, a plurality of layers of air are caused to whirl and form a rapidly spinning ring concentric with the piston and cylinder and into which ring the fuel streams are directed.

FREDERICK G. GRAVES.
